United States Patent Office

Des. 183,491
Patented Sept. 9, 1958

183,491

HAIR TREATING SOLUTION DISPENSER OR THE LIKE

Louis L. Lerner, Chicago, Ill., assignor to The Gillette
Company, Chicago, Ill., a corporation of Delaware

Application May 7, 1957, Serial No. 46,043

Term of patent 14 years

(Cl. D58—26)

Fig. 1 is a view in perspective of a hair treating solution dispenser showing my new design;

Fig. 2 is a top plan view;

Fig. 3 is a view in front elevation; and

Fig. 4 is a view in side elevation.

I claim:

The ornamental design for a hair treating solution dispenser or the like, as shown.
